UNITED STATES PATENT OFFICE.

GUY B. SCOTT, OF FRISCO, PENNSYLVANIA, ASSIGNOR OF ONE-HALF TO ELMER FRESHWATER, OF PAINESVILLE, OHIO.

TRIPPING MECHANISM FOR SCOOPS.

Application filed August 2, 1926. Serial No. 126,595.

My invention relates to tripping mechanism and particularly to mechanism of this character adapted for use with power excavators. The invention is utilized for tripping the latch controlling the discharge door of the excavator scoop. The object of the invention is to provide simple and conveniently-actuated mechanism of this character by which the door latch of the scoop may be controlled by the operator of the excavating machine, without the necessity of employing an additional man for performing this duty. Distinguishing the particular means for effecting this function from those shown, described and claimed in my application for U. S. Letters Patent, Serial No. 29,317, U. S. Patent No. 1,594,566, I utilize electrically operated means for tripping the scoop-door latch, the particular means shown in said patent being mechanically operated, the means of this application, similarly to those of the patent, for controlling the latch tripping members being connected to the main actuating lever for the scoop-actuating mechanism so that such trip controlling means are a part of a unitary device including such main actuating lever. It is intended that the trip controlling means shall be actuated by the same hand of the operator as actuates the main lever. The trip lever may be locked to the main lever so as to move therewith, or may have a selective limited movement independent of the main lever. In the former event, the movement of the main lever and the trip lever have no effect upon the scoop latch-control means.

The annexed drawings and the following description set forth in detail certain means embodying my invention, such means constituting, however, but two of the various forms in which the principle of the invention may be applied.

In said annexed drawings:

Figure 1 is a fragmentary side elevation of a conventional type of scoop excavator provided with one form of my improved electrically-operated tripping mechanism, the figure particularly showing the application of the tripping mechanism to a scoop of the so-called skimmer type, in which the scoop, in digging or filling, moves away from the excavator body;

Figure 2 is a fragmentary plan view, taken from the plane indicated by the line II-II' of Figure 1, this view showing a motor for dis-

engaging the scoop-door latch, the operation of which motor is controlled by means unitary with the main actuating lever, and actuated in the manner hereinafter fully described;

Figure 3 is an enlarged side elevation of a fragmentary portion of the main actuating lever and the associated trip-control members;

Figure 4 is a fragmentary side elevation of a conventional type of scoop excavator provided with the second form of my improved electrically-operated tripping mechanism, the scoop shown in this view being of the so-called dumper type, having a drop bottom and being adapted to be pulled toward the excavator body when being filled;

Figure 5 is a diagrammatic view of the wiring arrangement of the electric circuit, including the trip-actuating means; and

Figure 6 is an enlarged vertical cross-section, taken in the plane indicated by the line VI-VI, Figure 1.

Referring to the annexed drawings, in the several views of which the different elements are respectively designated by the same ordinals, I suggest one standard form of power scoop-excavating machine by a platform 5, Figure 1, a swinging boom 6 which is supported at one end by means of a horizontal pin 65 upon a boom support 64 pivotally mounted by means of vertical king-pins (not shown) upon forwardly projecting shoulder journals 63 secured to the platform 5, a scoop 7 depending from the boom 6 and adapted to be moved upon a trolley longitudinally of the boom 6 by means of power devices (well-known) actuated by standard control levers mounted upon the platform 5, said scoop 7 having a discharge door 30 controlled by a swinging latch 8. Mounted upon the platform 5 is a supporting frame 9 within the upper end of which is mounted a stationary transverse shaft 10 upon which is carried a freely-rotatable cable drum 11. One end of the cable drum 11 is formed into a housing extension 12, plainly shown in Figure 6, and secured at one end to the stationary shaft 10, and secured at its other end to the inside face of the housing 12, is a coiled spring 13 of a construction similar to that shown described and claimed in the pending application of Charles W. Krepps, Serial No. 60,379.

Connected at one end to the cable drum 11 is an insulated cable 39 which extends forwardly through a pulley block 60 and passes

at its opposite end to a motor 15 supported laterally of the boom 6 upon a base 16, as plainly shown in Figure 2. Mounted upon the extending end 17 of the motor shaft is a 5 drum 18, secured to said motor shaft end 17. A cable, rope, chain or other suitable flexible member 19 is secured at one end to the scoop-door latch 8 and is adapted to be wound from its other end upon the drum 18. The main 10 operating lever 41 of the excavator is formed with a contact 22 adapted to co-operate with a contact 21 secured to a trip lever 46 pivotally mounted upon the main lever 41 and normally held in the open position shown 15 in Figure 3 by means of the spring 42 connected to one end 46' of the trip lever 46, and at its other end to the main lever 41. The contact 22 is one terminal of an insulated cable 23 which passes to a battery or 20 other suitable source of power and thence to a terminal 23' mounted upon the supporting frame 9. Another terminal 23² is mounted upon the supporting frame 9, these two terminals co-operating with collector rings 25 formed on the drum 11, thus providing for 25 the completion of the circuit in any position of the drum 11.

I utilize the standard scoop-control lever 41 forming part of the standard excavator 30 mechanism in the operation of my improved tripping device. This lever 41 is reorganized in the following particulars. I replace the pin upon which the usual detent 26 is ordinarily pivoted, with a longer pin 54. As well 35 known, one type of standard scoop-control lever 41 is provided with a spring-controlled arm 43 connected at its lower end to one end of a centrally pivoted link 55 whose upper end is connected to the other end of the detent 40 26 adapted to engage at its lower end with the notched segment 27. The trip lever 46 is pivoted intermediate its ends upon the pin 54 and is normally held in the position shown 45 in Figure 3. It is evident that a finger or two of the same hand of the operator that is used for actuating the main excavator lever 41 will serve to pull the finger trip 46 in toward the handle portion 50 of the lever 41 so as to cause the contacts 21 and 22 to engage, 50 thus closing the circuit. When this happens, the motor 15 is started and thus winds the cable 19 upon the drum member 18, swinging the latch 8 upon its pivoted end to release the scoop door 30, and permit the scoop 7 to be discharged of its load. The winding 55 of the cable 39 upon the drum 11, under the influence of the spring 13 permits the slack in the cable 39 to be taken up when the motor 15 moves toward the excavator platform 5 as the trolley upon which the scoop 7 rides moves in toward the platform 5. Also, this cable 39 pays out from the drum 11 as the scoop 7 moves outwardly away from the platform 5 in its digging and filling operation. 60

The conduit 24 hereinbefore mentioned, surrounds the lever 41 and moves with the same and carries the wires 23 and 28 and is connected at the bottom by means of a swivel connection 34 with two other tubular conduit 70 members 48 and 49 carrying the wires 23 and 28, respectively, one to the battery and the other to the terminal 23² as also the wire 23 passing directly from the battery to the terminal 23'. 75

It is evident from the foregoing description that when the scoop 7 is filled and it is desired to move the latch 8, the trip 46 can be moved to close the circuit, whatever the position of the motor 15, due to the take-up provided by the drum 11, and the actuation 80 of the motor, will wind the cable 19 upon the drum 18 to release the scoop door 30.

In the form of device shown in Figures 4 and 5, the application of an electrically controlled trip to a scoop 7' of the type known as a drop bottom ditcher is shown, wherein the scoop door latch-releasing motor 47 is mounted upon the scoop-actuating arm 68 pivotally secured to the swinging boom 6. In this form 90 of device, the wiring diagram is plainly shown in Figure 5, and it will be noted that the conduit 48 is subdivided by a flexible joint 49' and extends up along the swinging boom 6 to provide a housing for the wires 36 and 37 leading to the motor 47. Further flexibility is provided by means of an end conduit portion 42 extending from the conduit 48 to the motor 47. In this form of device the latch-releasing cable 24' passes over a pulley 31 secured to the scoop-supporting arm 68 and is secured at its outer end to one end of the sliding latch 35 adapted to control the drop door 29 which normally closes the bottom of 95 the ditcher scoop 7'. 100

In both the forms of device shown in Figures 1 and 4, the doors 30 and 29 are closed by the usual manipulation of the operator, after the scoop contents have been discharged, this 110 feature of the action being standard and forming no part of my improvement.

What I claim is:

1. New and improved latch tripping means for use in excavator mechanisms having a scoop and a scoop-door retaining latch, comprising a main actuating lever provided with a manually-operable member having a selective movement independent of said lever, a pair of electrical contacts secured, respectively, to said lever and to said manually-operable member, means forming an electric circuit including a motor and said contacts, means normally holding said contacts apart, and a cable connection secured to the door-latch and adapted to be actuated by said motor. 115
2. Tripping mechanisms for excavator scoops comprising, in combination with the excavator and scoop and operating means therefor including a main actuating lever, a 120
3. A combination of parts including a main actuating lever having a manually-operable member, a pair of electrical contacts secured, respectively, to said lever and to said manually-operable member, means forming an electric circuit including a motor and said contacts, means normally holding said contacts apart, and a cable connection secured to the door-latch and adapted to be actuated by said motor. 125
4. A combination of parts including a main actuating lever having a manually-operable member, a pair of electrical contacts secured, respectively, to said lever and to said manually-operable member, means forming an electric circuit including a motor and said contacts, means normally holding said contacts apart, and a cable connection secured to the door-latch and adapted to be actuated by said motor. 130

scoop-door retaining latch, a motor mounted upon the excavator boom and formed with an extended shaft, a drum mounted upon and secured to said extended shaft, a flexible connection secured at one end to said latch and wound at the other end upon said drum, a trip lever pivotally mounted upon said main actuating lever, a pair of electrical contacts secured, respectively, to said main actuat-

ing lever and said trip lever, means forming an electric circuit including said motor and said pair of contacts, and means holding said circuit normally open, said trip lever being disposed adjacent the actuating handle portion of said main lever. 10

Signed by me this 31st day of August, 1926.

GUY B. SCOTT.
